RELEASING CLAMP

Kent A. Hawley, Baltimore, Md., assignor to
 Locke Insulator Corporation, Baltimore, Md.,
 a corporation of Maryland

Application July 31, 1930. Serial No. 472,036

19 Claims. (Cl. 248—31)

The invention relates to clamps employed for suspending conductors such as are used in high tension transmission lines.

It is well known that it is customary to suspend conductors by means of clamps carried by strings of insulators hung from towers which are frequently located long distances apart. It frequently occurs that sleet or ice may accumulate upon the conductor at one side of a tower and not at the other side owing to the existence of local storms and the difference in atmospheric conditions along the line. Furthermore, particularly where the line passes over the mountains or valleys, high winds may cause the bringing of a greater pressure upon the conductor at one side of a tower. Regardless of which may be the case, the fact remains that the strain is unequally distributed as that portion of the conductor which is coated with ice or sleet or that portion which is subjected to the action of high winds exerts a greater strain at one side of the tower than at the other. This is highly objectionable and it has occurred that towers have been pulled over. It is, of course, desirable to build the towers as light as possible to withstand the service for which they are intended and it is not practical to make them so strong as to be capable of withstanding every conceivable strain.

With the above facts in view I have devised the present invention which has for its general object the provision of a suspension clamp adapted to open and release the conductor upon the occurrence of an excessive strain at one side or the other of a tower so that the conductor may slide through until the strain is equalized, thus relieving the tower of those forces tending to pull it over.

An important object of the invention is to provide a clamp for this purpose which is capable of maintaining its grip until the string of insulators from which it is suspended has been pulled through an arc of a certain predetermined extent or moved into a certain angular position with respect to the normal or vertical, release occurring only after the safe angle or inclination has been passed.

Another object of the invention is to provide a clamp embodying cam means for holding it in a gripping relation to the conductor, the conductor itself supplying the force for effecting release when the cam means becomes ineffective.

A further object of the invention is to provide a clamp having suspension means located at the longitudinal axis of the conductor so

that the clamp may accommodate itself to vibrations of the conductor without exerting any bending strains thereon.

Yet another object of the invention is to provide a clamp of this character incorporating a spring means for maintaining a tight grip upon the conductor and compensating for any manufacturing variations in the parts.

Another object of the invention is to provide a clamp which may, by removing a few parts, be converted into the non-releasable type, if desired.

An additional object is to provide a releasing clamp which will be simple and inexpensive to manufacture, easy to assemble and install, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of a clamp constructed in accordance with my invention, and

Figure 2 is a vertical cross section taken on the line 2—2 of Figure 1.

Referring more particularly to the drawing, I have shown the device as comprising a main or lower clamping member 10 preferably formed as a casting and having a longitudinally extending cable seat 11 which is curved in cross section to fit the cable and which is also longitudinally curved. In other words this lower clamping member has preferably flaring or bell ends 12 so as to avoid contact of the edges thereof with the conductor and thereby eliminate the bringing of any bending strains upon the conductor in case of vibration or "dancing" of the conductor as is bound to occur in service.

It may be more or less an immaterial detail but the edges of this clamping member are here disclosed as having a somewhat thickened reinforcing bead 13 which merges into a transverse rib 14 located at the center. Furthermore this lower clamping member is shown as provided at opposite sides of its center with lateral trunnions 15 preferably having downwardly extending outer ends 16 for a purpose to be described. At each side and spaced from its center this clamping member is also provided with apertured ears 17.

The conductor 18 of course lies within this lower clamping member in engagement with

the seat 11 therein and is in turn engaged by an upper clamping member 19 having a groove or seat 20 therein curved in cross section to conform substantially to the cross sectional shape 5 of the conductor. This seat 20 is preferably longitudinally bowed upwardly as indicated in Figure 1 for a reason to be explained. At its opposite edges the clamping member 19 is provided with apertured ears 21 above and spaced from 10 the ears 17 and provided for the purpose of receiving the legs of U-bolts 22 which also pass through the ears 17 and which carry spring washers 23 and nuts 24. At its center the top surface of the upper clamping member 19 is 15 preferably grooved, channeled or recessed as shown at 25.

In conjunction with the clamp I provide suspension means here disclosed as comprising a pair of links or arms 26 having their lower ends 20 apertured at 27 for engagement upon the trunnions 15, the heads 16 of the latter preventing accidental disengagement after assembly has once been effected. Passing through the upper ends of these links is a bolt 28 carrying a nut 29, this bolt also passing through and pivotally connecting the links with a clapper-pan or socket member 30 of the type adapted to be engaged, for instance upon the headed pin of a supporting insulator or the like, not shown, above the 30 clamp.

The clamp further comprises pairs of presser levers 31 of a resilient character having downward projections 32 at their outer ends engaging upon the upper clamping member 19 and provided at their tops with retaining grooves 33 within which the bight portions of the U-bolts 22 are seated. These levers 31 are arranged in overlapping and staggered relation and their inner ends are pivotally connected as by a pin 34, 40 cottered at 35, with a fork 36 which has its upper end straddling and spaced from the bolt 28 and which is provided at its lower end with an extension 37 engaging within the groove or recess 25. Instead of stating that there are actually 45 pairs of levers, another way of describing the structure is to state that there are two levers, each of which is bifurcated to provide separate arms which are joined toward the outer ends. This is, however, a mere matter of terminology 50 and is of no consequence.

When the clamp is assembled and engaged upon the conductor, it is of course apparent that the member 10 is beneath the conductor, the member 19 is thereabove while the U-bolts 22 55 straddle it. As long as the fork 36 is in its normal or upright position, as shown in the drawing, the extension 37 reacting against the bottom of the groove or recess 25 will cause the ends 32 to press downwardly on the top of the end 60 portions of the upper clamping member. Of course the extension 37 itself exerts a high degree of pressure and it is for this reason that the seat 20 is preferably upwardly bowed, this 65 bowing compensating for any downward deflection which may occur at the center of the upper clamping member so that under strain the seat 20 will probably be, at least to all intents and purposes, straight. The clamp is tightened upon the conductor by drawing up on the nuts 24 70 on the U-bolts and it is apparent that by this means the gripping pressure of the clamp upon the conductor may be made as strong as desired. Under normal circumstances the suspension elements 30 and 26 as well as the fork 36 will remain in vertical position and there will 75

be nothing whatsoever to interfere with the clamping action. However, in case there is a heavier strain on one side of the clamp than on the other, for instance as the result of the formation of ice on one span and not upon the next span, there will be a tension exerted tending to swing the clamp and the string of insulators, not shown, supporting the same into a position considerably inclined with respect to the normal or vertical position. When this occurs, it is clear that the bolt 28 will strike against one side or the other of the fork 36. As the angularity increases a certain critical point is reached where the extension 37, which really constitutes a cam, will ride off from or out of the recess or groove 25. There is then no reaction against the pin 34 and the inner ends of the presser levers 31, together with the pin 34, 8 may drop down until they engage against the top of the central portion of the upper clamping member 19. There is consequently nothing exerting an upward strain against the bight portions of the U-bolts 22 and their holding action is therefore suddenly reduced, relieving the pressure of the upper clamping member 19 against 9 the conductor and permitting the conductor to slip through the clamp until the strain on the conductor at both sides of the clamp is equalized. The actual downward movement of the inner ends of the presser levers 31 under these 105 conditions may be as little as one-sixteenth of an inch but I have discovered that this is ample to permit the cable to slip through and equalize the strains. The exact distance is of course immaterial and depends obviously on the proportion of the parts, the location of the pivot or fulcrum points, etc. 110

In case it is so desired, the clamp may be used without the releasing feature in which event the fork 36 and presser levers 31 are omitted together with their connecting pin 34. Shorter U-bolts can then be used or if those shown at 22 have their legs threaded a sufficient distance, the nuts 24 may simply be turned up so as to effect the clamping action on the cable, the bight 120 portions of the U-bolts then bearing upon the upper clamping member 19 instead of upon the levers. It is thought this possible employment will be obvious.

From the foregoing description and a study 125 of the drawing it will be apparent that I have thus provided a simply constructed, inexpensive and easily installed clamp and one which will be capable of performing all the functions for which it is intended. It is believed that the construction, operation and advantages will be readily apparent to one skilled in the art without further explanation.

While I have shown and described the preferred embodiment of the invention, it should 135 be understood that the disclosure is merely an exemplification of the principles involved as the right is reserved to make all such changes in the details of construction as will widen the field of utility and increase the adaptability of the 140 device provided such changes constitute no departure from the spirit of the invention or the scope of the claims hereunto appended.

Having thus described the invention, I claim: 1. A suspension clamp comprising a pair of 145 clamping members engageable upon opposite sides of a conductor, bolt means urging said clamping members toward each other, suspension means, and pivoted trip operated means for rendering said bolt means ineffective upon 150

- swinging of said suspension means beyond a predetermined limit.
2. A releasing clamp comprising a lower clamping member adapted to support a conductor, an upper clamping member, suspension means pivotally connected with the lower clamping member, bolt means urging said clamping members toward each other, and pivoted means operating upon lateral swinging of the suspension means beyond a predetermined extent to render said bolt means ineffective. 80
3. A releasing clamp comprising a lower clamping member adapted to support a conductor, an upper clamping member, suspension means pivotally connected with the lower clamping member, bolt means urging said clamping members toward each other, and pivoted means operating upon lateral swinging of the suspension means beyond a predetermined extent to render said bolt means ineffective, said last named means being trip operated. 85
4. A clamping device comprising a clamping member adapted to support a conductor, a second clamping member, bolt means engaging both clamping members, suspension means connected with one clamping member, rigid means coacting with the upper clamping member and the bolt means for maintaining the clamping relation, and pivoted means operable upon swinging movement of the suspension means through a predetermined arc for rendering said last named means ineffective. 90
5. A suspension clamp comprising a pair of clamping members, bolts connecting the same, suspension means pivotally connected with one clamping member, a trip member engaging the upper clamping member and reacting thereagainst, means connected with the trip member and engaging the bolts and the upper clamping member for causing a reaction between them to maintain said clamping members in clamping engagement upon a conductor, and means operating upon swinging of the suspension means beyond a predetermined limit for releasing said trip. 95
6. A suspension clamp comprising a pair of clamping members engageable upon a conductor, bolts connecting said members, suspension means pivotally connected with one clamping member, a trip bearing normally upon and reacting against one clamping member, presser means pivotally connected with the trip and reacting against the bolts and one clamping member for normally maintaining the clamping members in clamping relation upon the conductor, and means operating on swinging movement of the suspension means beyond a predetermined limit for moving said trip and rendering said presser means ineffective. 100
7. A suspension clamp comprising a pair of clamping members, bolts connecting the same, suspension means pivotally connected with one clamping member, trip and presser means reacting against one clamping member and the bolts, and means operating on swinging movement of the suspension means beyond a predetermined extent for rendering said trip and presser means ineffective. 105
8. A suspension clamp comprising a pair of clamping members, bolts connecting the same, suspension means pivotally connected with one clamping member, trip and presser means reacting against one clamping member and the bolts, means operating on swinging movement 110 of the suspension means beyond a predetermined extent for rendering said trip and presser means ineffective.
9. A suspension clamp comprising a pair of clamping members engageable upon a conductor, retaining means engaging the clamping members, suspension means pivotally connected with one clamping member, and pivoted trip operated means for releasing said retaining means upon swinging movement of the conductor beyond a predetermined limit. 115
10. A clamping device comprising a clamping member adapted to support a conductor, a second clamping member, bolt means engaging both clamping members, suspension means connected with one clamping member, pivoted means coacting with the upper clamp member and the bolt means for maintaining the clamping relation, and pivoted means operable upon swinging movement of the suspension means through a predetermined arc for rendering said last named means ineffective. 120
11. A clamping device comprising a clamping member adapted to support a conductor, a second clamping member, bolt means engaging both clamping members, suspension means connected with one clamping member, pivoted means coacting with the upper clamping member and the bolt means for maintaining the clamping relation, other means pivoted to said pivoted means for normally maintaining the same against movement, and means operable upon swinging movement of the suspension means through a predetermined arc for rendering said last named means ineffective. 125
12. A suspension clamp comprising a clamping member adapted to support a conductor, a second clamping member, U-bolts embracing said clamping members, suspension means pivotally connected with one clamping member, means reacting against the upper clamping member and the bight portions of said U-bolts for maintaining the clamping relation, and pivoted means operable upon swinging movement of the suspension means beyond a predetermined limit for rendering said last named means ineffective. 130
13. A suspension clamp comprising a pair of clamping members engageable upon a conductor, U-bolts embracingly engaging said members, suspension means pivotally connected with one clamping member, pivoted means reacting against the upper clamping member and the bight portions of the U-bolts, other pivoted means pivotally connected with said first named pivoted means for normally maintaining the clamping relation of the members upon the conductor, and means operable upon swinging movement of the suspension means beyond a predetermined limit for rendering said last named means ineffective. 135
14. A suspension clamp for a conductor comprising a pair of clamping members, suspension means therefor, and trip operated lever means engaging one clamping member at a plurality of points for normally maintaining the clamping members in clamping engagement upon the conductor and cooperating with the suspension means for releasing the clamping action upon movement of the suspension means beyond a predetermined extent. 140
15. A conductor suspension clamp comprising clamping members, a plurality of levers normally maintaining the clamping members in 145

clamping relation, suspension means, means for holding the lever in effective position, and means cooperating with the suspension means for moving said holding means out of engagement with the levers upon movement of the suspension means beyond a predetermined extent.

16. A conductor suspension clamp comprising clamping members engageable upon a conductor, lever means reacting against one clamping member at a plurality of spaced points for normally maintaining a clamping action upon the conductor, swingable means normally maintaining said lever means effective, suspension means,

10 15 and means cooperating with the suspension means upon movement thereof beyond a predetermined extent for swinging and rendering said maintaining means ineffective.

17. A conductor suspension clamp comprising 20 a pair of clamping members engageable upon a conductor, means reacting against one clamping member at opposite sides of the center thereof for normally maintaining the clamping members in clamping engagement upon the conductor, means normally maintaining said means

effective, suspension means, and means operable upon abnormal movement of the suspension means for releasing said maintaining means.

18. A conductor suspension clamp comprising 80 a pair of clamping members, U-bolts carried by one member and straddling the other, levers engaged within the bight portions of the U-bolts and reacting against the adjacent clamping member, means normally holding said levers stationary, suspension means, and means 85 operable upon movement of the suspension means beyond a predetermined extent for releasing said holding means.

19. A conductor suspension clamp comprising 90 a pair of clamping members engageable upon a conductor, levers located above the clamping members and reacting downwardly thereon, means normally holding said levers against movement whereby they will maintain the clamping members in clamped engagement upon the conductor, suspension means, and means 95 cooperating with the suspension means for releasing said levers.
